UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

SERVICE-METER FOR TELEPHONE-LINES.

No. 795,551.

Specification of Letters Patent.

Patented July 25, 1905.

Application filed September 26, 1904. Serial No. 225,969.

To all whom it may concern:

Be it known that I, CHARLES E. SCRIBNER, a citizen of the United States, residing at Jericho, in the county of Chittenden and State of Vermont, have invented a certain new and useful Improvement in Service-Meters for Telephone-Lines, of which the following is a full, clear, concise, and exact description.

My invention relates to a measured-service system of telephone-exchange, and has for its object to provide a simple and efficient arrangement of circuits and apparatus whereby each call from a line is automatically registered when the central-office operator answers the call.

My invention contemplates a telephone-line having an electromagnetic service-meter associated therewith in a circuit controlled through the agency of a device at the substation. The circuit is completed when the subscriber sends in a call, and the magnet being energized the meter is thereby placed or "set" in operative condition. The central-office operator is provided with a pair of link conductors and a connection - switch for uniting said conductors with the line, said connection - switch being adapted in closing to render the service-meter magnet inert by disconnecting the same from the line and so causing the operation of the meter.

I will describe my invention by reference to the accompanying drawings, wherein—

Figure 1 is a diagram illustrating a telephone-line extending from a substation to a central office, together with an operator's cord-circuit for making connection therewith, the system being equipped and operating in accordance with my invention; and Fig. 2 shows the central - office equipment of a telephone-line illustrating a modified form of my invention.

The same characters of reference are used to designate the same parts in both figures.

Referring first to Fig. 1, I have shown a telephone-line extending in two limbs 1 2 from a substation to a central office, where they pass through the contacts of the usual cut-off relay *c* to the poles of the grounded central battery *b*, the limb 1 including a line signaling device, which may consist of a relay *a*, controlling a local circuit 3, including the line-lamp *d*. The limbs 1 2 are also connected with the line-terminals of multiple-spring jacks *e e*, the rings or thimbles *e* of said jacks being connected

together and to earth through the winding of cut-off relay *c* by a conductor 4. The apparatus at the substation is of the usual character, comprising transmitting and receiving telephones in a bridge of the line conductors, said bridge being controlled at the contacts of the usual gravity switch-hook *s*, and a call-bell and condenser in a permanently-closed bridge of the line. The circuit of the line is open as to battery - currents when the telephone-receiver is on its hook; but the bridge containing the telephone apparatus is closed at the contacts of the switch-hook when the receiver is taken for use. The magnet *f* of the service-meter or connection-register is included in line conductor 2 between the back contact of the cut-off relay and the grounded pole of the battery. The armature *f'* of said magnet when energized completes the continuity of a conductor 5, extending from the free pole of battery *b* or from conductor 3 to the armature *c'* of cut-off relay *c*, included in conductor 2, so completing a locking-circuit for magnet *f*, comprising conductors 3, 5, and 2, such circuit being under the control of the cut-off relay. A resistance *f*⁵ is included in said circuit to prevent said circuit from short-circuiting the telephone-line. The armature *f'* of said magnet is adapted when energized to bring a pawl *f*² into such relation to the train of counting-wheels *f*³ of the meter that when the armature is retracted through the agency of a spring *f*⁴ said pawl will operate the counting-wheels to record the call. The operator's cord-circuit is of the usual type, comprising plugs *g g'* with link conductors 6 7, extending between the tip and ring contacts, respectively, of said plugs, the battery *b* being located in a bridge of said conductors between the windings of the usual repeating-coil. The sleeve-contacts *g*² *g*³ of the plugs *g g'* are connected by conductors 8 9, respectively, with the free pole of battery *b* and include supervisory signals *h h'*, respectively, under the control of the usual supervisory relays *i i'*, included in conductor 7 and associated with the answering and calling plugs *g g'*, respectively. While I have shown two batteries in the drawings, (each marked *b*,) it will be understood that these may be and usually are one and the same battery.

The operation of the system is as follows: When the telephone at the substation is taken for use, current is permitted to flow from the free pole of battery *b*, over the conductor 1,

through the winding of the relay a , through the substation apparatus, and back by way of limb 2, through the winding of magnet f of the service-meter to the grounded pole of battery b . The line-relay a upon being thus energized attracts its armature and closes the local circuit 3, including the line-lamp d . The magnet f of the service-meter in drawing up its armature f' brings the pawl f^2 in position to operate the counting-wheels f^3 when the armature is retracted and also closes a locking-circuit for itself by way of conductors 3 5 2, including contacts of the cut-off relay. The central-office operator in response to the call inserts plug g into the answering-jack e of the line, thereby bringing the conductors 6 7 into connection with the limbs 2 1 of the telephone-line and completing a circuit for cut-off relay c by way of conductors 8 and 4 and the thimble e^3 and sleeve g^2 of the spring-jack and plug. The plug g and jack e may thus be considered as a connection - switch adapted to temporarily unite the link conductors 6 7 with the line. The cut-off relay when thus energized draws up its armatures, disconnecting the battery b and line signaling apparatus from the line and opening at its armature c' the local locking-circuit 3 5 2 of magnet f , and said magnet becoming inert allows its armature f' to be retracted by spring f^4 , whereupon the pawl f^2 operates the counting-wheels of the meter to record the call.

Referring now to Fig. 2, I will describe a slightly-modified form of my invention. In this form the magnet f is provided with two windings l l' , one of which windings l is included in a parallel branch 10 of the local circuit 3, including the line-signal. The magnet when initially excited by the closure of the circuit of winding l at the contacts of line-relay a is adapted to complete a local locking-circuit 11, including the other winding l' of the magnet f , which circuit extends from the free pole of battery b , through armature f' of magnet f and its normally open contact, through an extra armature c' of the cut-off relay c and its back contact, winding l' of magnet f , to earth. The pawl f^2 is thus set in position to operate the counting - wheels when the armature is retracted. When the call is answered by the insertion of a plug into a jack of the line, the cut-off relay is energized and opens at its armature c' the local locking-circuit 11 of the magnet f and also de-energizes line-relay a to open the circuit, including winding l of magnet f , whereupon the armature f' is retracted by spring f^4 to cause the pawl f^2 to operate the counting-wheels f^3 of the meter and register the call.

I claim—

1. The combination with a telephone-line, of an electromagnetic service-meter therefor, a circuit for the service-meter magnet including a source of current, a device at the sub-

station of the line controlling said circuit, link conductors at the central office, a connection-switch for uniting said link conductors with the line, said service-meter magnet being rendered inert by the closure of said connection-switch to record the call.

2. The combination with a telephone-line, of a source of current in the line, and a switch at the substation for controlling current therefrom, a line-signal and an electromagnetically-actuated service-meter associated with the line and responsive to said substation-switch, and switch-contacts actuated in answering a call as indicated by the line-signal to sever the connection of the line-signal and service-meter with the line to record the call; whereby the electromagnet of the service-meter is energized in making a call, and is rendered inert in answering a call to record the same, as described.

3. The combination with a telephone-line, of a connection-switch at a central office for uniting said line with another, a cut-off relay operated in closing said connection-switch, a line-relay and a battery normally connected in the line-circuit at the central office through contacts of said cut-off relay, a telephone-switch at the substation controlling the flow of current through said line-relay, a service-meter for the line having an actuating magnet-winding in a local circuit controlled by said line-relay, and a local locking-circuit for said service-meter closed by a relay-contact operated by the magnet thereof, said locking-circuit being adapted to be opened by the cut-off relay.

4. The combination with a telephone-line, of a service-meter for the line at a central office, comprising an electromagnet and registering mechanism operated thereby, a switch at the substation, and means controlled by said switch for exciting the service-meter magnet, a local locking-circuit for the service-meter closed in the response thereof, a connection-switch to unite said line with another, and means actuated in closing said connection-switch for de-energizing said service-meter magnet.

5. The combination with a telephone-line, of a service-meter comprising an electromagnet, the armature thereof, and registering mechanism actuated by a complete oscillation of said armature, of means controlled by a device at the substation of the telephone-line for exciting said magnet, a connection-switch at the central office adapted to unite said line with another, and means actuated in closing said connection-switch for de-energizing said service-meter magnet, whereby a registration of the meter is effected, substantially as set forth.

6. The combination with a telephone-line, of an electromagnetic service-meter therefor, a circuit for said meter controlled through the agency of a device at the substation, a central-office connection-switch, a relay adapted when energized to render said service-meter magnet

inert to record the call, and a circuit for said relay controlled by said connection-switch.

7. The combination with a telephone-line extending from a substation to a central office, of a connection-register associated with the line at the central office a magnet controlling the same, a circuit for said magnet, a switch at the substation adapted to complete said circuit and actuate said magnet to set the register, a connection-switch associated with the

line at the central office, and means actuated in closing the same adapted to render said magnet inert to operate the connection-register.

In witness whereof I hereunto subscribe my name this 16th day of September, A. D. 1904.

CHARLES E. SCRIBNER.
